UNITED STATES PATENT OFFICE.

EDWARD J. QUIGLEY, OF NEWARK, NEW JERSEY.

COMBINATION-GARMENT.

1,143,228.

Specification of Letters Patent. Patented June 15, 1915.

Application filed August 13, 1913. Serial No. 784,560.

To all whom it may concern:

Be it known that I, EDWARD J. QUIGLEY, a citizen of the United States, and a resident of the city of Newark, county of Essex and State of New Jersey, have invented certain new and useful Improvements in Combination-Garments, of which the following is a specification.

This invention relates to combination garments and the objects of the invention are to make a combination garment that can be made either as underwear or as a shirt with drawers attached.

Further objects of the invention are to improve the back of the garment.

To the accomplishment of the above objects and to such others as may hereinafter appear the invention comprises a garment which is cut on a line from the center of 20 the back of the waist to the knee at the outer side of the drawers.

In the drawings the figure is a back view of a garment showing the improved back made in accordance with my invention.

Referring to the drawings, 1 designates the body of an undergarment, or union suit, to which is secured the drawers 2, in the present instance shown as of knee length, although the same may be made longer if so desired.

In the figure is shown the back of the garment, which can be applied to any form of garment of the union type, which is open on

a curved diagonal line 10 from the point 11 at the center of the waist line, to the point 12 at the side of the knee, the opening being closed by means of buttons 13 or other suitable means. When the back is unbuttoned the same can be folded back, as shown in dotted lines, affording a very large opening that is very conveniently opened or closed. In a back so constructed the buttons when placed as shown, are not in the way of the wearer when seated, which is a great advantage.

While the invention has been described with particular reference to the details of construction, the same is not to be considered as limited thereto, as many changes can be made and still fall within the scope of the invention set forth in the following claim.

I claim—

A combination garment comprising in a one piece suit, shirt and drawers, the back of said drawers comprising the seat being cut on a diagonal line from the waist line to the outer side of one of the drawer legs.

In testimony whereof I have signed this specification in the presence of two subscribing witnesses.

EDWARD J. QUIGLEY.
